Primary Examiner—Ralf Seifert

[57] CLAIM

The ornamental design for a adjustable lighter holder, as shown.

DESCRIPTION

FIG. 1 is a front elevational view of an adjustable lighter holder showing my new design;

FIG. 2 is a rear elevational view;

FIG. 3 is a right side elevational view;

FIG. 4 is a front elevational view, shown in position of use;

FIG. 5 is a front perspective view of FIG. 1; and,

FIG. 6 is a perspective view shown in a position of use. The broken line showing of a lighter is for illustrative purposes only and forms no part of the claimed design.
